UNITED STATES PATENT OFFICE.

WILBERT J. JACKMAN, OF LIMA, OHIO.

APPARATUS FOR BURNING HYDROCARBON OIL.

SPECIFICATION forming part of Letters Patent No. 634,463, dated October 10, 1899.

Application filed February 17, 1898. Serial No. 670,694. (No model.)

To all whom it may concern.

Be it known that I, WILBERT J. JACKMAN, a resident of Lima, in the county of Allen and State of Ohio, have invented certain new and useful Improvements in Apparatus for Burning Hydrocarbon Oil; and I do hereby declare the following to be a full, clear, and exact description of the invention, such as will enable others skilled in the art to which it appertains to make and use the same.

My invention relates to an improvement in apparatus for burning hydrocarbon oil for heating purposes, one object of the invention being to so construct a stove adapted to burn hydrocarbon oil that the full heat from the burner shall be utilized to the best advantage and so that the heat shall be effectually radiated.

A further object is to provide an apparatus for burning hydrocarbon oil for heating purposes which shall be simple in construction, comparatively cheap to construct, and which shall be effectual in all respects in the performance of its functions.

With these objects in view the invention consists in certain novel features of construction and combinations and arrangements of parts, as hereinafter set forth, and pointed out in the claims.

In the accompanying drawings, Figure 1 is an elevation of my improved apparatus. Fig. 2 is a vertical sectional view. Fig. 3 is a horizontal section.

A represents the base of my improved stove, on which an air-tight oil-tank 1 is located. A perforated ring 2 is located on the oil-tank, and this ring supports a plate 3. A space is thus left between the top of the oil-tank and the plate for the circulation of air which may enter through the perforations of the ring 2. The plate 3 also serves to protect the oil-tank from heat of the burner located above it, and the circulation of air under this plate and over the oil-tank will assist in ventilating the latter and keeping it cool. A cylinder 5 is supported by the plate 3 and incloses the combustion-chamber, and this cylinder may be provided with one or more doors 6, whereby to give access to the combustion-chamber, and with other openings for the accommodation of portions of the burner B, located within said combustion-chamber.

The burner may be of any preferred form of construction, but for convenience of illustration I have shown the burner as comprising a coiled pipe 7 and suitable heating and starting devices 8, located under the same. This burner is supplied with oil from the tank or receptacle 1 by means of a pipe 8^a, having a suitable valve 9. Air-pressure is supplied to the oil by means of a pump 9^a of any preferred form of construction through a pipe 10, communicating with the receptacle 1, and oil will be supplied to the tank through a filling-funnel 11, having a suitable valve 12. A pressure-gage C will preferably be provided and communicates by a short pipe 24 with the air-pipe 10, and as the latter has free communication with the oil-tank it is apparent that the pressure in the latter will be indicated by the gage.

A drum C' is located some distance above the combustion-chamber and supported solely by means of a series of pipes or flues 25 26 27. The flue 25 communicates at its lower end with the interior of the combustion-chamber and extends through the drum C', the upper end of said flue constituting, in effect, a thimble 28 for the attachment of a suitable pipe to conduct products of combustion to a chimney and also afford proper draft for the stove. The pipe or flue 25 is provided at or near its upper end with a damper 29 and at or near its lower end with a damper 30. The flue 26 also communicates at its lower end with the combustion-chamber; but at its upper end this flue communicates with the interior of the drum C'. The flue 27 communicates at its upper end with the interior of the drum C', but is closed at its lower end and does not communicate with the combustion-chamber. A transverse pipe or flue 31 connects the flue 27 with the direct or draft flue 25 at a point above the damper 30 in the latter. From this construction and arrangement of parts it will be seen that when the damper 30 in flue 25 is closed the heat and products of combustion will ascend through the flue 26 and enter the drum C', through which they will pass, and then pass downwardly through the flue 27 to the short transverse pipe or flue 31, by which the heat and products of combustion will be conducted to the direct flue 25 and by the latter will be

conducted to the chimney-pipe 32. During this passage of the heat and products of combustion through the flues and drum these parts will be highly heated, and the air between and around them will be effectually heated, so as to quickly and properly heat the room in which the stove is located at a small cost for fuel.

The pipes 25 26 27 may, if desired, be ⁵ enclosed by a cylinder E of open-work.

My improvements are simple in construction, comprise comparatively few parts, operate effectually to supply heat and light to the room in which the apparatus is located, ¹⁵ and are effectual in all respects in the performance of their functions.

Various slight changes might be made in the details of construction of my invention without departing from the spirit thereof or ²⁰ limiting its scope, and hence I do not wish to limit myself to the precise details herein set forth.

Having fully described my invention, what I claim as new, and desire to secure by Letters ²⁵ Patent, is—

1. The combination with a combustion-chamber and a drum above the same, of a flue in open communication at its ends with the drum and combustion-chamber, a direct ³⁰ flue communicating directly with the combustion-chamber and extending through the drum without means of communication therewith, means for closing communication between said direct flue and the combustion-chamber, a third flue communicating at its ³⁵ upper end with the drum and closed at its lower end, and a transverse flue connecting said last-mentioned flue with the direct flue above the top of the combustion-chamber.

2. In a vapor-stove, the combination with a ⁴⁰ combustion-chamber and a vapor-burner located centrally therein, of a drum disposed above the combustion-chamber, a flue communicating at its respective ends with the combustion-chamber and drum, a flue communicating with the combustion-chamber directly over the burner therein and extending upwardly through the drum without communication therewith, means for closing communication between said last-mentioned flue and the combustion-chamber, a third flue above ⁴⁵

the combustion-chamber, said third flue closed at its lower end and communicating at its upper end with the drum, and a transverse flue connecting said third flue with the ⁵⁵ central flue above the combustion-chamber.

3. The combination with a combustion-chamber and a drum disposed above the same, of flues disposed upon the combustion-chamber and supporting the drum, one of said ⁶⁰ flues in open communication with said combustion-chamber and drum and another of said flues closed at its lower end and in open communication at its upper end with the drum, a direct flue in open communication ⁶⁵ at its lower end with the combustion-chamber, said direct flue passing upwardly from the combustion-chamber and through the drum without means of communication with the latter, a transverse flue connecting the flue ⁷⁰ which is closed at its lower end, with the direct flue at a point above the point of communication of the latter with the combustion-chamber, and a damper in the direct flue between the transverse flue and combustion-chamber, substantially as set forth. ⁷⁵

4. A stove consisting of a drum inclosing a combustion-chamber and provided with a door, a burner located within said combustion-chamber, a drum above the combustion-chamber, two flues disposed between the combustion-chamber and drum above the same, both of said flues communicating with said drum and only one of them communicating with the combustion-chamber, a direct flue ⁸⁰ communicating with the combustion-chamber and passing through the upper drum without means of communication therewith, means for closing communication between said direct flue and the combustion-chamber, a flue ⁸⁵ connecting the direct flue with the flue which does not communicate with the combustion-chamber, and a cylinder of open-work inclosing said flues.

In testimony whereof I have signed this ⁹⁰ 95 specification in the presence of two subscribing witnesses.

WILBERT J. JACKMAN.
